[57] **CLAIM**

The ornamental design for a modular video cassette display rack, as shown and described.

DESCRIPTION

FIG. 1 is a top, front, and left side perspective view of a modular video cassette display rack showing my new design, the broken-line depiction of a video cassette being for illustrative purposes only and forming no part of the claimed design;

FIG. 2 is a top plan view thereof;

FIG. 3 is a front elevational view thereof;

FIG. 4 is a bottom plan view thereof;

FIG. 5 is a rear elevational view thereof; and

FIG. 6 is a left side elevational view thereof, the right side being a mirror image of that shown.

FIG 1
